CLAIM

The ornamental design for a coffee maker, as shown and described.

DESCRIPTION

FIG. 1 is a perspective view of a coffee maker.

FIG. 2 is a right elevation view of the coffee maker of FIG. 1.

FIG. 3 is a left elevation view of the coffee maker of FIG. 1.

FIG. 4 is a front elevation view of the coffee maker of FIG. 1.

FIG. 5 is a rear elevation view of the coffee maker of FIG. 1.

FIG. 6 is a top plan view of the coffee maker of FIG. 1.

FIG. 7 is a bottom plan view of the coffee maker of FIG. 1; and,

FIG. 8 is an enlarged view of the handle of the portafilter of FIG. 1 shown separately for ease of illustration of the claim. The wire frame lines shown throughout the views are intended to indicate surface contour.

1 Claim, 8 Drawing Sheets
